PHOTOGRAPHIC RECORDING MACHINE

James W. Bryce, Bloomfield, N. J., assignor, by
mesne assignments, to International Business
Machines Corporation, New York, N. Y., a cor-
poration of New York

Application December 12, 1932, Serial No. 646,827

6 Claims. (Cl. 235—60)

This invention relates to a novel machine for preparing a photographic film record of numerical information or data which was entered into and/or calculated by an accounting machine or 5 other keyboard controlled data entering machine and further to the provision of a machine of this type in which such numerical data may be photographically recorded upon a film in proximity to a photographically recorded reproduction of a 10 document.

In its broader aspects the invention relates to a photographing recording machine for providing photographic records of numerical data entered into the machine under key control and accordingly the invention in its broader aspects is not 15 limited to accounting machines.

Films as prepared in the machine which forms the subject matter of the present application are adapted for use in certain accounting and statistical 20 operations in other machines and the machines for utilizing such novel films will be subject matter of separate applications.

Accordingly, one object of the present invention resides in the provision of a photographic recording machine for providing a photographic film record of representations of numerical data entered into the machine from a keyboard.

A further object of the present invention resides in the provision of a combined accounting and photographic recording machine adapted to 25 photographically record representations of numeral data entered into the accounting machine under the control of parts of the accounting machine.

A further object of the present invention resides in the provision of a combined accounting and photographic recording machine adapted to photographically record representations of results of computations performed by the accounting machine under the control of elements of the 30 accounting machine.

A further object of the present invention resides in the provision of a combined accounting machine and photographic recording machine with provisions for controlling the latter machine 35 from the former.

A further object of the present invention resides in the provision of a combined accounting and photographic recording machine in which 40 numerical and/or result data entered into and/or computed by the accounting machine may be recorded photographically in juxtaposition to a reproduction of a document which was related to or formed the source of information entered into 45 or computed by the accounting machine.

Other and more incidental objects reside in the provision of a combined photographic recording and accounting machine in which supplemental 50 manual set up data and/or serial number data

and/or miscellaneous supplemental data may be recorded photographically along with the other numerical data.

A further object of the present invention resides in the provision of a machine of the above mentioned type in which a series of successively equi-spaced photographic records may be recorded in compact form upon a film.

A further object of the present invention, according to one embodiment thereof, is to provide 10 a combined accounting and photographic recording machine in which item entries may be placed on one film and results upon another film and also in the provision of a machine adapted to place both the item entries and results upon one 15 and the same film.

Further objects of the present invention reside in the provision of a combined accounting and photographic recording machine wherein representations of data are set up in the photographic recording machine under the control of elements of the accounting machine and in which the actual photographing including film feed and exposure, is initiated automatically during actuation of the accounting machine.

A further object of the present invention resides in the provision of a combined photographic recording and accounting machine with novel 20 controls intermediate various parts of the two sections of the machine.

Further and other objects of the present invention will be hereinafter set forth in the accompanying specification and claims and shown in the drawings which by way of illustration show what I now consider to be preferred embodiments 30 of the invention.

In the drawings:

Figure 1 is a top plan view of the machine;

Figs. 2 and 2a taken together show a part side 40 elevational and part sectional view of the machine, the section being taken substantially on line 2—2a of Fig. 1 looking in the direction of the arrows. Fig. 2a is substantially a side elevational view of the adding machine or entry section with the case removed and Fig. 2 is substantially a 45 vertical sectional view of the recording section of the machine;

Fig. 3 is a detail sectional view taken substantially on line 3—3 of Fig. 2 and shows the driving means and clutches for the film drive and the 50 shutter device of the camera;

Fig. 4 is a detail sectional view of certain parts shown in Fig. 3, the section being taken substantially on line 4—4 of Fig. 3;

Fig. 5 is another detail view taken substantially on line 5—5 of Fig. 3;

Fig. 6 is a sectional plan view of a part of the photographic recording section of the machine, the view being taken substantially on line 6—6 60

of Fig. 2. This view shows a check in position on the bed and also shows the recording elements for recording numerical information;

Fig. 7 is a detail sectional view taken substantially on line 1—1 of Fig. 6 and shows the manner in which a numerical slide cooperates with the mask element;

Fig. 8 is a transverse sectional view of this part of the machine taken substantially on line 8—8 of Fig. 6;

Fig. 9 is a detail view of certain parts at the right hand side of the adding machine within the case, the view being taken substantially on line 9—9 of Fig. 1 and looking in the direction of 15 the arrows;

Fig. 10 is a circuit diagram of the machine which forms one embodiment of the invention;

Fig. 11 is a detail top plan view of a modified form of camera recording device for separately 20 recording items and totals;

Fig. 12 is an elevational and part sectional view of the modification shown in plan in Fig. 11. The view is taken substantially on line 12—12 of Fig. 11;

Fig. 13 is a detail view of certain clutch and driving parts for the modified form of machine, the section being taken substantially on line 13—13 of Fig. 11;

Fig. 14 is a wiring diagram of the machine 30 forming the modified embodiment of the invention;

Fig. 15 is an enlarged detail view of certain parts shown on Fig. 11. This view is also a detail view of parts shown on Fig. 13, being 35 taken on line 15—15 of Fig. 13; and

Fig. 16 is a fragmentary section of a portion of the film which is produced showing data recorded thereon.

Before describing the details of the structure 40 of the machine, a brief description will be given of the operations which the machine is intended to perform. The present machine incorporates a keyboard entry section shown as an adding machine of known type which is arranged for 45 printing items, taking totals, sub-totals and transfer totals, etc. Associated with the adding machine is a photographic recording device which is arranged to record on a film the numerical data entered into the adding machine 50 and the total data derived by the adding machine. For each entry into the adding machine and for each total printed by the adding machine on the usual adding machine tape a record is made of representations upon a film in the 55 form of dots or spots which by their relative location to each other on the film represent the numerical data entered or totaled by the adding machine. Provision is also made in the photographic recording section for recording photographically when desired, a reproduction of a 60 check or other document. Such check or like document can be photographed on the film in juxtaposition to numerical data records derived from the adding machine. Provision is also 65 made for photographically recording a serial number which is representative of the number of the particular photographic record. Provision is also made for photographically recording hand set up numerical data which may be representative of dates or other information. In the photographic recording section provision is also 70 made for recording the kind of total taken by the adding machine, for example, sub-totals, grand totals, transfer totals, etc. According to 75 a modified embodiment of the invention pro-

vision is made for recording the item data entered into the adding machine on one film and for photographically recording the total data on a separate film.

Referring now to Figs. 1 and 2a, the adding 5 machine which is used to illustrate a suitable type of keyboard controlled machine is here shown as a machine of the well known Burroughs type. The adding machine proper and here illustrated, is the adding and listing machine shown and described in the United States patent to Vincent and White, No. 919,656, dated April 27, 1909. Since according to the present embodiment a motor driven type of adding machine is provided the arrangement for motor 10 drive of the machine is of the type shown in the United States patent to Vincent, No. 1,054,628, dated February 25, 1913. The adding machine will only be described briefly since reference may be made to the foregoing patents for a fuller 20 description.

The machine comprises a set of numeral keys 100 (Fig. 1), an elimination key 101 corresponding to key 265E of the Vincent and White patent, a transfer total key 102, a sub-total key 103 and a total key 104. These latter keys correspond to keys 265T, 265S and 265 of the Vincent and White patent. There is also provided the motor bar 105, corresponding to the motor bar shown in the Vincent patent. The adding machine comprises also the usual two accumulators generally designated 106 and 107 (see Fig. 2a). The adding machine comprises also the usual type sectors controlled from the item entering keyboard and from the accumulators and which sectors are generally designated 108 in Fig. 2a. Such sectors correspond to part 618' of the Vincent and White patent.

Referring now to Fig. 9 this figure shows a portion of the linkage intermediate the motor bar 105 and the motor driven clutch. This mechanism is generally similar to the mechanism shown in Fig. 1 of the Vincent patent. Shaft 109 (Fig. 9) corresponds to shaft 200C of the Vincent and White patent and this shaft 41 is adapted to be rocked to differential extents on different total taking operations. Shaft 110 of Fig. 9 corresponds to the shaft 6 of the Vincent patent and such shaft 110 in the present machine is utilized not only for driving the adding and listing machine but for also driving the photographic recording mechanism. For this purpose the shaft 110 at its opposite end (see Fig. 2a) is provided with a gear 111 which drives a gear 112 fixed to a shaft 113 which extends 50 to the photographic recording section of the machine.

The connections from the adding and listing machine section to the photographic recording section comprise three trains of mechanism. 60 One train of mechanisms extends from the various type sectors 108, another train comprises the shaft 113 just referred to and another train comprises a link connection to the shaft 109 previously referred to. The train to the sectors 65 108 will be first described.

Referring to Figs. 1, 2 and 2a, each of the type sectors 108 has connected to it an upstanding arm or link 114, each of which at its upper end connects to a lever 115. Each of these levers 70 115 at its rear end (see Fig. 2) connects to a downwardly depending link 116 which in turn, through a bell crank member 117 is adapted to displace a horizontally disposed link 118. To aid in the displacement of these parts 114, 115, 116, 75

117 and 118, springs 119 are provided. Each link 118 has connected to it a slide member 120 (see Fig. 7) which is slidably mounted in the base plate of the recording section of the machine 5 and arranged to be slidably displaced beneath the perforated mask 121. Each of the slide members 120 carries an indicia indicating spot 122 which is preferably darkened. The top surface 10 of the mask is preferably light or white in color and the other portions of the top of the slide 121, except for the indicia spot 122, are also white. Alternatively the indicia spot may be light and the rest of the top of the slide may be dark and the top of the mask may be dark. By referring 15 to Fig. 6 it will be noted that by differentially displacing the slides 120 the spots 122 will present an appearance through the mask 121, the same as they would if these dark spots were painted on the top of the masks at the different index point locations. In this manner any setting of 20 the type sectors 108 of the adding machine will set up a corresponding arrangement of spots through the perforated mask and set up representations of numerical data. The openings 25 through the mask preferably have a spacing corresponding to the index point positions of a tabulating card, see the patent to Lake No. 1,772,492. It will be understood that there is a slide 120 for each type sector 108. A supplemental slide 120T is also provided for indicating total and transfer total data. The supplemental slide is disposed beneath the extreme right hand columns of openings through the mask and such supplemental slide 120T is operated by a horizontal link 118T (see Fig. 2) which cooperates 30 with a lever 117T connected to a link 116T (Fig. 2a). 116T at its forward end connects to a lever 123 which is fixed to a rock shaft 124 (see Fig. 9), extending across under the adding 35 machine and having fixed to its opposite end a lever 125 to which a vertical extending link 126 is connected. The link 126 at its upper end connects to an arm 127 which is fixed to the shaft 109. The shaft 109 is differentially rocked in 40 total taking operations and the train of linkage just described is adapted to differentially shift the total recording slide 120T in the photographic recording section for setting up representations of total designating data to be photographed. 45 For the purpose of restoring the total linkage just described a supplemental restoring spring 128 can be provided (see Fig. 9).

Referring again to Fig. 6, the mask 121 is provided with an angle plate 129 disposed adjacent the numerical data zone of the mask. In the use of the machine a document such as a check 55 130 can be placed by hand in position abutting this angle plate and the data from this check can be photographically recorded. The photographic recording section is provided with a check receiving opening in the front of the housing and to the left of the left side of the adding machine (see Fig. 1) so that the check can be placed in position by hand.

60 Referring again to Figs. 2 and 6, there is an opening 131 provided through the mask through which the numeral wheels 132 of a Veeder type counter can be viewed and photographed. This Veeder type counter is of the customary step by 65 step variety and is preferably electromagnetically actuated by a rocking armature member 133 which is adapted to be rocked by the energization of an actuating electromagnet 134. In Fig. 2 reference character 135 shows the housing for 70 the wheels of the counter.

If desired (see Fig. 6) other data such as the name of a bank, etc., may be printed on the top of the mask in any desired location, here shown in proximity to the counter opening 132, such data being indicated at 136. In certain 5 cases it may be desirable to set up by hand representations of supplemental numerical data. For this purpose the mask 121 is provided with a supplemental zone beneath which there are disposed a number of hand set slides 120S. These slides 10 are similar in construction to the slides 120 previously referred to and they may be moved by hand through members 118S to set up representations of fixed data which are to be photographically reproduced with the variable 15 numerical data.

The mask is preferably provided with a black line 137 for providing a reference line indicating mark on the film upon photographing. Such reference line is shown in the film (Fig. 16) 20 as 137a.

Photographic recording device

Referring further to Figs. 2a and 9, the shaft 110 makes one complete rotation upon each depression of the motor bar 105 and upon each 25 motor driven actuation of the adding machine. This rotation of shaft 110 is utilized for effecting and controlling the operations of the camera element including film feeding and exposing. 30

Referring to Fig. 2 the shaft 113 at its end, through gearing 138, drives a vertical shaft 139, which vertical shaft in turn through gearing 140 (see also Fig. 1) drives (see Fig. 3) the notched element 141 of an electromagnetic one revolution 35 clutch (see also Fig. 4) which is revolvably mounted on a clutch shaft 142. The complementary part of this one revolution clutch comprises a pawl carrier arm 143 fixedly carried on the clutch shaft 142. 143 has pivotally secured to it the 40 usual pawl or dog 145 which is adapted to be released to engage with the notch of the element 141 upon the rocking of the armature 146 upon the energization of the clutch magnet 147.

Film feed

The clutch shaft 142 has fixed to it a mutilated gear 148 (Fig. 5) and a locking element 149 of a Geneva device. The mutilated gear co-acts with the gear 150 and the locking element 149 cooperates with the other part of the geneva designated 151. Gear 150 through an idler 152 drives a gear 153. Gears 150 and 153 are respectively fixed to sprocket shafts 154 and 155. Upon engagement of the electromagnetic one revolution clutch the sprocket shafts 154 and 155 will be turned one-quarter of a revolution to advance the film in the camera 156, (see Fig. 2). The sprocket shafts have the usual film feeding sprockets 157 and 158 driven thereby. The film 60 is advanced by the drive just mentioned from a supply roll 159 to a take-up roll 160. The take-up roll is preferably driven by a slipping belt drive connection 161.

Shutter actuation

In Fig. 2 the part generally designated 162 is the shutter of the camera which may be of any desired type. The usual lens is in association with the shutter. The shutter operating shaft 70 is designated 163. Referring now to Fig. 5 provision is made for rocking the shutter operating shaft 163 after the film has been fed. For rocking this shutter shaft a cam member 164 is provided fixed to the gear 148 (see also Fig. 3) and 75

such cam 164 is adapted to rock a spring restored lever 165 and therethrough rock the shutter shaft 163 and effect exposure of the film.

The camera 156 as shown in Fig. 2 is mounted 5 a distance up above the mask and for illuminating the mask, lights 166 may be provided.

The operation of the machine will now be generally described.

It will be understood that data may be photographically recorded from an inserted document 10 or the recording of data from the document may be dispensed with. Under the assumption that check data is to be entered on the adding machine and the check recorded, the operation 15 would be as follows. The operator of the machine first sets up on the amount keys on the adding machine or keyboard section the desired data from the check. After the data has been read from the check and entered on the adding 20 machine keyboard, the operator places the check in position in the photograph recording section against the abutment 129. Thereafter the operator depresses the motor bar 105 of the adding machine. The operating cycles of the adding 25 machine ensue and during the early part of the rotation of the shaft 110, a section of film is fed forward in position for receiving an image. While the film is being fed forward the sectors 108 of the adding machine move toward the 30 printing line. Such movement of any sector from its normal no print position to beyond the zero position displaces a bail 167 (Fig. 2a) upwardly to cause a contact spring 168 to ride off of an insulated block 169 and establish contact 35 with a conducting segment strip 170. The relation of parts is such that contact between 168 and 170 is not established unless some particular sector of the group of sectors has moved to bring a significant figure to the printing line. This 40 control is provided for suppressing film feed and photographic recording operations when the adding machine is making an idle stroke. The movement of the sectors 108 to printing position differentially displaces the slides 120 to set up 45 a proper representation of the data which is to be photographically recorded under control of the adding machine or keyboard entry device through the mask.

Referring to Fig. 2a, a commutator 171 is also 50 provided on shaft 110 having a single conducting spot 172 adapted to cooperate with brushes 173 upon the rotation of the commutator.

Referring now to Fig. 10, the camera clutch 55 magnet 147 and the serial number magnet 134 are disposed in a circuit which extends to the wiping contact element 168. The segment 170 is connected in a circuit to one of the brushes 173 and the other brush 173 is connected back to the other side of the line. The segment strip 60 172 on the commutator 171 is in such relation on the commutator that it will complete a circuit through the camera clutch magnet 147 and the serial number magnet 134 just after any type 65 sector has moved past the zero position and effected the completion of the circuit between 168 and 170. Accordingly, during the movement of the type sectors 108 to printing position for printing a significant number, entered 70 into the adding machine from the keyboard, film feed will be initiated. At the time the type hammers of the adding machine take their imprint from the type sectors the shutter device is timed to be operated and to cause an exposure to be 75 taken of the representations appearing on the

mask and of the inserted check or other document.

On total taking operations there is an idle operating cycle of the adding machine before total taking. On such idle stroke, film feed and exposure of the film will not occur since under this idle operation 168 will not establish contact with 5 170. However, on the subsequent actual total printing operations the contact will be established and there will then be recorded on the 10 film a representation of the total together with the character of the total, the representation of the character of the total being obtained through the supplemental slide 120T.

The modified embodiment will now be described. According to the modified embodiment of the invention, two camera devices 156L and 156T are provided (see Fig. 11). On ordinary item listing entering operations photographic records are made by camera 156L, but when total 15 data is to be recorded, camera 156L is shifted out of exposing position and out of operation and camera 156T is shifted into exposing and operating position. With the two camera form of device, the camera 156T is the totaling camera 20 and the camera 156L is the listing camera. These two cameras are mounted and secured together in a frame 174 (Figs. 11 and 13) which is slidably mounted in guideways. To shift the two cameras, links 175 are provided (Figs. 11 and 12) which 25 connect with two levers 176 fixed to a rock shaft 177 having a cam follower 178 connected thereto cooperating with a cam 179. Upon rotation of the cam 179 the camera 156L is carried away from 30 exposing position and the camera 156T is brought 35 to exposing position. The cameras are restored back to normal position with 156L in list position by a spring 180. Each of the cameras is provided with an individual clutch for driving the film feed and actuating the shutter. The clutch magnets are designated 147T and 147L in Fig. 11. The clutch element 141 (see Fig. 15) instead of being driven by gearing 146 direct from the vertical 40 drive shaft 139 as in the other embodiment is driven in the following manner. Fixed to each 45 clutch element 141 is a gear 140a which meshes with a gear 140b which is splined to a splined shaft 140c. Splined shaft 140c through gearing 140d, is driven from the vertical drive shaft 139. It will be understood that the two clutch devices 50 with their cameras can slide along the splined shaft 140c and either camera can be operated by rotating the splined shaft provided the particular camera clutch is called into action. In order to shift the cameras a shift drive is provided which will now be described. Fixed to shaft 55 139, in the modified embodiment, adjacent the cam 179 is a gear 181 (Fig. 12) which drives a gear 182 (Fig. 11) which is freely rotatable on the cam shaft 163. The pawl 184 of the camera 60 shifting one revolution clutch is adapted to be engaged with the notched element 185 of the one revolution clutch upon movement of armature 186. This armature is displaced by the energization of the camera shifting clutch magnet 65 187.

Referring now to Fig. 9, on totaling operations link 116T is shifted to the right. The shift of this link to the right will permit the three-blade contacts which comprise the contact pair 188 and 70 189 to shift to allow 188 to open and 189 to close.

Upon listing operations contacts 188 will remain closed and the circuit to the list camera clutch magnet 147L will be completed in a same manner as previously described for the other embodiment 75.

ment, i. e from line through 147L, contacts 188, 168, 170, 173 and 172 to the other side of the line. Upon listing operations the camera shift clutch magnet 187 will not become energized because contacts 189 do not become closed.

On totaling operations contacts 188 open and contacts 189 become closed. The opening of contacts 188 prevents energization of the clutch magnet pertaining to the list camera and closure of contacts 189 permit the energization of both the total camera clutch magnet 147T and the camera shifting clutch magnet 187.

With the usual operation of the Burroughs machine on totaling operations there is an idle stroke before totaling. Photographic recording operations are suppressed on such idle stroke by reason of the contact 168 and segment strip 170. On the idle stroke 168 does not establish contact with 170 and accordingly the circuit cannot be completed to any of the clutch magnets or to the serial number magnet 134. However, on a totaling stroke the circuit will be established to the total camera clutch magnet 147T and to the camera shift clutch magnet 187. With the camera shift clutch magnet 187 energized, both cameras will be shifted so as to carry 156L away from exposing position and to bring 156T into exposing position. The arrangement is such that the exposure is not made on camera 156T until this camera has been shifted to exposing position. A switch 190 can be provided which when in the position shown, provides for total recording by the total camera 146T. With the switch placed in the dotted line position, both item records and total records will be recorded by the list camera 146L. In short this switch when in dotted line position makes the modified embodiment operate like the first described embodiment.

Referring to Fig. 16 this shows a fragmentary section of a film produced by the photographic recording section. On this section of film, 200 are the feed sprocket apertures in the film. The data represented at 201 represents a reproduction of a document. The data representations in zone 202 represents amounts set up from the hand setup devices. The data at zone 203 represents numerical data entered from the keyboard of the machine. In the upper photographic record the data at 204 represents the class of total operation and the data at 205 represents numerical result data derived from the accumulating section of the accounting machine.

The serial number reproduction is indicated at 206 and the supplementary data from the mask is indicated at 207. It will be understood that the completed film has photographic reproductions thereon at successively spaced intervals along the film and that the reproductions are in extremely compact form. The films used may be negative films or films which during development are reversed to positives. The film delineated is a positive.

What I claim is:

1. A combined photographic recording accounting machine with a photographic recording section including photographing recording means and an accounting section with accounting elements, said photographic recording section including devices controlled from the accounting elements of the accounting section and representing variable control data, means in the photographic section under control of elements of the accounting machine for selectively control-

ling the photographing of representations of data according to whether the data represents entries into the accounting section of the machine or results computed by the accounting section of the machine.

2. The invention set forth in claim 1 in which a representing device is provided in the photographic recording section for controlling the photographing of designating data according to the kind or result data which is set up and derived from the accounting machine, said representing device being under control of elements of the accounting machine.

3. The invention set forth in claim 1 in which means is provided for controlling selectively the making of one film record or another film record according to whether a record is to be of an item entered into the accounting machine or a result computed by the accounting machine.

4. The invention set forth in claim 1 in which the photographic recording section comprises two camera devices each with film feeding mechanism and exposure controlling means and including means for selectively calling the film feed and exposure means of one camera into operation while suppressing the action of such parts of the other camera.

5. A combined photographic recording and accounting machine with a photographic recording section and an accounting section, said latter section including a main operating means and devices upon which data is set up, representing devices adapted to be photographed in the recording section which are controlled by the data set up devices of the accounting section, film feeding and exposure controlling means in the recording section, means operating said last named means from the main operating means of the accounting section to feed and expose a length of film for each effective operation of the main operating means of the accounting section, and means for suppressing film feed and exposure in the event that the said representing devices are not displaced to significant figure representing position.

6. A machine of the class described, comprising in combination an accounting machine with item entry means therefor, a photographic recording section for making a photographic control record of accounting data derived from the accounting machine, and representing devices controlled by the item entry means of the accounting machine for setting up in the photographic recording section in proximity to an adjacent clear background and in variable relation thereto representations of numerical data to be photographed by the photographic recording section, said setup representing devices when variably disposed in an otherwise clear zone representing by their relative disposition therein the control value of such representations when photographed by the photographic recording section, and means for receiving, retaining and aligning a document having numerical data inscribed thereon in juxtaposition to the representing means for corresponding numerical data so that a reproduction of such document with its numerical data may be photographically made upon a common record in juxtaposition to the photographic control record of corresponding numerical data.
